UNITED STATES PATENT OFFICE.

HARDY T. WILKES, OF GREENVILLE, FLORIDA, ASSIGNOR OF ONE-HALF TO J. H. BOYD, OF OLUSTEE, FLORIDA.

GATE-LATCH.

1,028,646.

Specification of Letters Patent. Patented June 4, 1912.

Application filed April 8, 1911. Serial No. 619,810.

To all whom it may concern:

Be it known that I, HARDY T. WILKES, a citizen of the United States, residing at Greenville, in the county of Madison and 5 State of Florida, have invented new and useful Improvements in Gate-Latches, of which the following is a specification.

This invention relates to gate latches, and the objects are to provide a simple device 10 of this character including a gravity controlled latch member and a support therefor, the support being designed for attachment to a fence post or other stationary object adjacent to the gate and being provided with means for movably supporting 15 the latch member and for holding the same with a portion exposed for manual manipulation so as to permit the latch member to be readily disengaged from the keeper plate 20 of the gate.

Another object of the invention is to provide in the support means for causing positive movement of the latch member and to prevent the same from binding in the support when the member is engaged by the gate on the closing movement thereof.

In the drawing, forming a portion of this specification and in which like numerals of reference indicate similar parts in the several 30 views:—Figure 1 is a perspective view of a portion of a gate and a portion of a fence structure showing my improved latch in its applied position. Fig. 2 is a longitudinal section through the support for the latch 35 member, the latch member being shown in its locked position in full lines and in its released position in dotted lines.

The latch structure comprises a head or support 1 provided preferably at one end 40 with a screw 2 which is embedded in the post A of the fence structure shown. The support extends outwardly at right angles to the post, and as illustrated, it is provided with parallel longitudinal portions 3 which 45 are connected with each other at their outer ends, at 4. The members are also connected with each other by a horizontally disposed longitudinally combined stock and fulcrum member 5, the upper surface of which being 50 flush with the upper surfaces of the side members 3 for a purpose to be hereinafter described. The member 5 of the support is formed at its outer end with a downwardly and forwardly curved bearing surface 6, the 55 rear of the member being provided with a

similar but rearwardly extending surface 7, the former being positioned with respect to the portion 8 of the support and the sides 3 thereof so as to form therewith an intervening relatively long passage 9. The surface 6 is positioned with respect to the portion 4 of the support and the sides 3 thereof so as to form therewith an intervening relatively short passage 10. The movable keeper element comprises a ring 11 which is confined between the portions 3 of the support, being positioned therebetween and normally supported by the member 5 of the support, it being understood that under the weight of the ring 11 it will normally assume a locked position, the major portion of the ring being disposed below the plane of the support so as to provide a peripheral contacting surface below the plane of the surface 6 of the member 5.

The gate B carries a latch plate 12. This plate has one of its ends extended beyond one side of the gate and positioned with respect to the ring 11 so that the latter forms an obstruction. Incident to the fact that the ring 11 gravitates to normally assume the full line position shown in Fig. 2, the peripheral contacting surface of the ring at a point below the bearing surface 6 of the member 5 will be engaged by the latch plate of the gate, such engagement being sufficient to cause the inner walls of the member 5 to engage against the bearing surface 6 so that the latter will operate as a fulcrum, the impact of the gate against the ring causing the latter to be moved upwardly to the dotted line position shown in Fig. 2. After the keeper member has passed entirely beneath the ring 11 and disengaged therefrom the ring will fall by gravity to the full line position shown in Fig. 1 of the drawing, whereupon, the latch plate will have its opposite surface engaged with the peripheral surface of the ring 11 as will be understood. In this position of the ring 11 and the latch plate 12 the gate will be held against movement in one direction. By providing the member 5 with the plurality of surfaces 6 and 7 they are engaged with the inner walls of the ring 11 so as to hold the ring in a position where the uppermost portion of the opening will be exposed, as at C in Fig. 2, so as to permit the insertion of the finger thereinto when it is desired to lift the ring 110 to its released position from the latch plate.

I claim:—

In a latch of the class described, a latch plate secured to the gate, a gravity closing ring, a support for the ring, said support comprising spaced parallel side members being formed at their center to provide a horizontally disposed longitudinal fulcrum member; the said member having its ends formed to provide oppositely inclined curved surfaces adapted to engage the inner surface of the said ring and operate as a fulcrum, said surfaces being further adapted to sup-

port the ring so as to expose the uppermost portion of the ring opening above the said fulcrum member whereby the finger may be inserted between the ring and said member substantially as and for the purpose described. 15

In testimony whereof I affix my signature in presence of two witnesses.

HARDY T. WILKES.
